PRECISION RESISTOR

Filed Jan. 27, 1947

Fig. 1

The diagram shows a series circuit. On the left, a vertical line labeled K_3 has a horizontal line extending to the right. This line passes through a zigzag symbol representing a resistor. From the right end of this line, another vertical line extends upwards, labeled K_4 . This vertical line K_4 has a small horizontal line extending to the right at its top, with an arrow pointing to the right. From the bottom of this vertical line K_4 , a horizontal line extends to the right, ending at a small circle labeled K_2 . From this same small circle K_2 , a vertical line extends downwards, ending at a small circle labeled K_1 . From the bottom of this vertical line K_1 , a horizontal line extends to the right, ending at a small circle labeled K_2 .

PRECISION RESISTOR

Seth August Holmqvist, Appelviken, Sweden, assignor to Telefonaktiebolaget L M Ericsson, Stockholm, Sweden, a company of Sweden

Application January 27, 1947, Serial No. 724,627
In Sweden February 18, 1946

8 Claims. (Cl. 201—48)

1

The invention refers to precision resistors provided with potential-terminals. The manufacturing of precision resistors, also includes an adjustment of each resistor in order to ascertain the resistor having the proper resistance value. Said adjustment, hitherto being a very tedious work, is often performed by successively removing small portions of the resistance, wire until the resistance, with the desired degree of accuracy, has the proper value. My invention intends to produce such a resistor, at which the work necessary for the adjustment is considerably simplified. The invention is characterized by one of the ends of the resistor being connected to one end of an adjusting resistor, the value of which is 0.1 to 0.001 of the value of the first mentioned resistor, and by an adjustable contact member, connected to one of the terminals of potential of the precision resistor, being arranged to be set in an arbitrary position along the adjusting resistor and possibly to be locked in set position.

The invention will be described more closely with reference to the accompanying drawing, in which Fig. 1 is a wiring diagram showing an adjustable precision resistor consisting of ten resistor units with a switch arranged for connexion of an arbitrary number of said units and with auxiliary circuits necessary for the adjustment of said units. Fig. 2 shows an application of the invention to a fixed resistor. On the drawing, 1, 2—10 indicate the different resistor units, 11, 12, 13 etc. indicate outstretched resistance wires, each being connected between two units following each other, 15, 16, 17 etc. indicate the sliding contacts, which can be moved along the pertaining resistance wires 11, 12, 13 etc., and which are connected through wires 33, 34, 35 etc. to contacts 21, 22, 23 of the switch, the turnable arm of which is indicated by 31. One end of the resistor unit 1 is connected over wire 32 to contact 20 and to potential terminal K1, and the turnable arm 31 is connected to potential terminal K2. The same end of said resistor unit is also connected to current terminal K3, and one end of resistance wire 14 is connected to current terminal K4. On adjustment, a circuit comprising the variable resistance RR, a source of current B and a standard resistor RN are connected to the terminals K3, K4, said standard resistance RN moreover being connected by its ends over line L to contacts 41, 43 of a switch A, connected to a compensator K, shown on the drawing as a Dubois Raymond compensator. The terminals K1 and K2 are connected to the contacts 40, 42

2

of the switch A, compensator K may, by means of switch A, be connected alternately to terminals K1, K2 or resistor RN. The compensator being known per se consists of a battery E, an adjustable resistor RD, a sliding contact S and a galvanometer G. The resistance of the standard resistor RN is suitably chosen equal to the desired resistance of each of the resistor units 1—10. Supposing that the resistor unit 1 is to be adjusted, the current intensity through resistor units 1—10 and standard resistor RN is first regulated by means of resistor RR to suitable value, whereupon the position of sliding contact 8 along resistor RD is regulated until the galvanometer G shows 0. During this, the arms A of the switch must rest on contacts 41, 43. The arms A of the switch are thereafter moved to contacts 40, 42 and sliding contact 15 is moved along wire 11 until the galvanometer shows 0. It is then ascertained, that the resistance of the resistor unit 1 plus the resistance in wire 11 right to sliding contact 15 equals the resistance of standard resistor RN, the resistance of resistor unit 1 thereby being adjusted to its proper value. The sliding contact is locked in the set position, e. g. by means of a screw, which may possibly be sealed. The turnable arm 31 must rest on contact 21 during said measurements. If resistance unit 2 is thereafter to be adjusted, contact 21 is connected to potential terminal K1, the connection between contact 20 and terminal K1 thereby being broken. The arm 31 is then turned so as to rest on contact 22. The measurements described in connection with the adjustment of resistor unit 1 are now repeated, the resistance value of resistor unit 2 thereby also being adjusted. In the same way, the resistance value of the other resistor units 3—10 can also be adjusted. If any of the resistor units is to be given a resistance value differing from the value of the other units, standard resistor RN may naturally, on adjustment of said unit, be changed for a resistor, the value of which equals the value of the desired resistance of said unit. Instead of the shown compensator K any other compensator may naturally be used. It is also possible, when adjusting, to use another method of comparison, in which method the resistance over e. g. resistor unit 1 and that part of wire 11, being connected to said unit, and being limited by sliding contact 15, is compared to some known resistor. The resistance value of the adjusting wire, e. g. 11, must naturally be considerably lower than the resistance value of resistor unit 1, and the relation between first mentioned and last mentioned

resistance value will be dependent on the desired accuracy of adjustment. For the greatest accuracy occurring in the practice, said relation should be ca. 0.001 whilst said relation should be ca. 0.1 by the lowest accuracy occurring in the practice. The resistance of the adjusting wires by unity of length is also suited to the desired accuracy of adjustment. When a great accuracy of adjustment is desired, a certain displacement of the sliding contact along the wire must give a relatively small difference of the resistance, and in said case the resistance of the adjusting wire per unity of length should then be low.

The rheostat shown in Fig. 1 contains ten resistor units. The number of resistor units may naturally be arbitrary. In case it is desired to adjust only one fixed precision resistor, only one adjusting wire is needed. Fig. 2 shows how the resistors will in said case be connected to the terminals K₁—K₄. The resistance wires 11, 12 etc. shown in Fig. 1 to be straight, outstretched wires, may naturally also be arranged along an arc, the sliding contacts 15, 16 etc., thereby being arranged on a turnable arm. Instead of a single wire, a coil-wound wire known per se in rheostats may be used.

The invention is naturally not limited to the embodiments shown above, but can be modified in several different ways within the scope of the idea of the invention.

I claim:

1. Precision resistor provided with two current terminals and two potential terminals and comprising a main resistor and an auxiliary resistor, said resistors being connected in series, the resistance value of said auxiliary resistor being 0.1 to 0.001 of the resistance value of said main resistor, the free end of said main resistor being connected to one of said current terminals one of said potential terminals being connected to a point on said main resistor and the free end of said auxiliary resistor being connected to the second of said current terminals, and an adjustable contact member being designed to be set in an arbitrary position along said auxiliary resistor and being connected to the second of said potential terminals.

2. Precision resistor provided with two current terminals and two potential terminals and comprising a number of part resistors, said part re-

sistors being connected in series, each part resistor consisting of a main and an auxiliary resistor, said last mentioned two resistors being connected in series, the resistance value of each of said auxiliary resistor being 0.1 to 0.001 of the resistance value of said belonging main resistor, an adjustable contact member for each of said auxiliary resistors, each of said contact members being designed to be set in an arbitrary position along the belonging auxiliary resistor, and to be connected to an appertaining contact in a switching device designed to connect an arbitrary of said last mentioned contacts to one of said potential terminals, the free end of the first of said part resistor being connected to one of said current terminals one of said potential terminals being connected to a point on said main resistor, and the free end of the last of said part resistors being connected to the second of said current terminals.

3. Resistor according to claim 2, wherein each of said auxiliary resistors consists of an outstretched resistance wire.

4. Resistor according to claim 2, wherein each of said auxiliary resistors consists of a coilwound wire.

5. Resistor according to claim 2, wherein each of said adjustable contact members is designed to be locked in set position.

6. Resistor according to claim 1, wherein said auxiliary resistor consists of an outstretched resistance wire.

7. Resistor according to claim 1, wherein said auxiliary resistor consists of a coilwound wire.

8. Resistor according to claim 1, wherein said adjustable contact member is designed to be locked in set position.

SETH AUGUST HOLMQVIST.
